UNITED STATES PATENT OFFICE

THOMAS C. RALEY, OF ST. LOUIS, MISSOURI, ASSIGNOR TO GETZ EXTERMINATORS, INC., 61
OF ST. LOUIS, MISSOURI, A CORPORATION OF MISSOURI

DISTRIBUTOR FOR INSECTICIDES AND THE LIKE

Application filed January 16, 1932. Serial No. 587,090.

This invention relates generally to distributors of the type employed for scattering insect powders and other insecticides about, and more specifically to a device of this type 5 which is of such improved structure and arrangement that it performs its function better and is more durable than similar devices heretofore known.

Fig. 1 is a side elevation of the improved 10 distributing device.

Fig. 2 is a vertical section taken through the device illustrated in Fig. 1.

In the drawing, wherein is shown for the purpose of illustration, merely, one embodiment 15 of the invention, A designates the device of the invention generally, said device including a container B and a discharge spout C. The container B comprises a top element 1 formed of suitable rigid material, 20 said top element being provided with an up-standing, tubular inlet member 2 which is provided with screw-threads formed at the outer face thereof. Also, this upstanding, tubular inlet member is provided with an 25 inturned annular flange 3 at its top, as shown in Fig. 2. The screw-threaded inlet member 2 is adapted to receive a screw-threaded cap 4, said cap including a screw-threaded, annular side wall 4^a and a top wall 30 4^b. When the cap 4 is applied to the up-standing inlet member 2 the screw-threads of the side wall thereof engage the screw-threads of said inlet member, and the lower face of the flat top wall 4^b of the cap contacts 35 with the top face of the annular flange 3 of said inlet member to provide a tight joint between the cap and the inlet member. The side wall 1' of top element 1 is provided with an annular depression 5, which is intended 40 for a purpose to be hereinafter set forth.

The device A includes also a bottom element 6 with which the discharge spout C is associated, said bottom element comprising a 45 substantially flat bottom wall 6^a and an up-standing annular side wall 6^b in which an annular depression 7 is formed. The bottom element is provided with an opening 8 through which the discharge spout is extended, 50 said discharge spout being pinched

together at its inner end, as indicated at 9 in Fig. 2, and being secured by solder 10 or other suitable means to the bottom member at the inner face thereof. The discharge spout C is open throughout its length forwardly of the pinched together inner end thereof to provide a passageway C', and apertures 11 are formed through the wall of said discharge spout so as to place the interior of the container B in communication 55 with the passageway C' through the discharge spout. 60

The side wall 12 of the container B is formed of rubber composition, said side wall preferably being in the form of a sleeve open 65 at its opposite ends. The container B is assembled by forcing the opposite ends of the sleeve which provides the annular side wall of said container over the annular side walls of the top and bottom elements 1 and 6, wire elements 13 then being arranged about the opposite ends of said sleeve and drawn tight and secured in place in such tightly drawn condition so as to force portions of said sleeve into the depressions 5 70 and 7 of the top and bottom elements, respectively. A coil spring 14 is arranged within the container B, said coil spring contacting at its opposite ends with portions of the top and bottom elements of the container. 75

In the use of the improved device, insecticide in the form of powder, for instance, is introduced into the container through the inlet member 2, after which the cap 4 is replaced on said inlet member. This powder is discharged from the container through the apertures 11 and discharge spout C by forcing the top and bottom elements of the container toward each other, the annular side wall of the container collapsing on such movement of the top and bottom members and the coil spring returning the container to its extended condition after the pressure which caused such movement has been discontinued. 85

I claim:

1. A device of the class described comprising a container, said container including a top element having an inlet opening, a cap for closing said inlet opening, a bot- 100

- tom element having a bottom wall and a continuous upstanding flange, a discharge spout associated with said bottom element and arranged to communicate with the interior of
5 the container, said discharge spout being closed at its inner end and having openings formed therein forwardly of said inner end, said discharge spout being extended through an aperture formed through the upstanding
10 flange of said bottom element and the inner end of said discharge spout being secured to said flange of said bottom element at a point which is in opposed relation with respect to said aperture whereby a two-point support
15 for said discharge spout is provided, the relationship of said points of support of said discharge spout with respect to the bottom wall of the bottom element being such that a space is present between the discharge spout
20 and said bottom wall whereby material within the device may circulate entirely around the discharge spout, a side wall associated with said top and bottom elements and adapted to be collapsed on movement of said
25 top and bottom elements toward each other, and resilient means within said container which tends to restore said container to its extended position when the side wall thereof has been collapsed.
30 2. The device as set forth in claim 1, wherein the upstanding flange of the bottom element is provided with a continuous inwardly bent portion which provides an endless depression at the outer face of said
35 flange, and wherein the inner end of the discharge spout is secured to said inwardly bent portion of said flange in order to increase the rigidity of said discharge spout.
In testimony that I claim the foregoing
40 I hereunto affix my signature.

THOMAS C. RALEY.
